UNITED STATES PATENT OFFICE.

ADOLF BELER, OF PITTSBURG, PENNSYLVANIA, ASSIGNOR TO BELER WATER HEATER CO., OF PITTSBURG, PENNSYLVANIA.

HYDROCARBON-BURNER.

No. 899,003.

Specification of Letters Patent.

Patented Sept. 15, 1908.

Application filed October 31, 1907. Serial No. 400,014.

To all whom it may concern:

Be it known that I, ADOLF BELER, a citizen of the United States, residing at Pittsburgh, in the county of Allegheny and State of Pennsylvania, have invented a new and useful Hydrocarbon-Burner, of which the following is a specification.

This invention relates to hydrocarbon burners of that character particularly designed for use in connection with water heaters.

One of the objects of the invention is to provide a novel arrangement of burners below the coil of the heater whereby water of condensation falling upon the burners will not tend to extinguish the flames.

A still further object is to provide burners constructed in a simple and inexpensive manner and having efficient means whereby air may be thoroughly commingled with the fuel, all the parts of the burner being readily accessible for the purpose of cleaning them.

Another object is to provide a pilot burner of novel form having a novel arrangement of sections suitably shielded so as to prevent all parts of the pilot flame from being extinguished by wind.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a section through a heater embodying the present improvements. Fig. 2 is an enlarged longitudinal section through one of the burners. Fig. 3 is a face view of the head of the burner. Fig. 4 is a section through the pilot burner. Fig. 5 is an inverted plan view of the pilot burner, the lower shield plate removed.

Referring to the figures by characters of reference, 1 designates the casing of a heater which, in the present instance, is shown as a water heater, the same being provided with a coil 2 through which water is fed in the usual manner, said coil being preferably supported upon an inwardly extending flange 3 located within the casing adjacent the bottom thereof. This flange is preferably cast integral with a base 4 cylindrical or of other desired contour, said base having an integral horizontal partition 5 close to the bottom thereof. Formed integral with this partition is a

circular series of nipples 6 reduced toward their upper ends and having passages therethrough. Mounted upon the upper or reduced end of each nipple is a tubular standard 7 provided at its upper end with a hollow inclined head 8 provided with a tapered tubular core 9 extending through the center thereof. Standard 7 opens into the head below the core and said head has an inferior annular shoulder 10 from which extends a flange 11. This flange has its lower portion cut away as shown at 12 to form an outlet for the purpose hereinafter set forth. A cross strip 13 extends diametrically across the outer or small end of core 9 and resting upon this core is a cap comprising a circular plate 14 having an annular flange 15 which converges toward the plate and has a plurality of longitudinal slits 16 constituting outlets for fuel. Oppositely disposed openings 17 are formed within the plate 14 adjacent its center to permit the escape of air from core 9 through the center portion of the plate and any suitable means such as a screw 18 is utilized for fastening the plate 14 to the cross strip 13. A suitable number of openings 19 are formed within the core 9 and surrounded by flange 15 so as to direct air into the cap.

Although only two burners have been shown in Fig. 1 it is to be understood that a circular series of these burners is to be utilized and it will be noted that the burners are so disposed that the flames therefrom will be directed upwardly against the coil 2. It will also be seen that any water of condensation which might drip from the coil 2 will not tend to extinguish the flames but will flow downward upon the inclined plates 14 and around the flanges 15 and thence outward and downward through the outlets 12. As shown in Figs. 2 and 3 the slits 16 do not extend to the inner edge of each flange 15 and therefore water dripping into the head of the burner and passing around the cap thereof will not flow into the gas compartment 20 which is formed within the head and around the core and below the cap.

As is usual with devices of this character it is necessary to employ a pilot burner in connection with the main burner. In the present instance a pilot burner of novel form is employed. This burner is made up of four tubular arms 21 radiating from a nipple 22 and provided with outlet slits or openings 23 preferably disposed in staggered relation. 110

Nipple 22 is designed to engage a pipe 24 and interposed between the end of this pipe and the arms 21 is a guard plate 25 having a frusto-conical flange 26 extending downward therefrom. Another similar plate 27 is suitably secured above the arms 21 and is provided with a flange 28 similar to flange 26. Webs 29 are disposed radially between the two plates and their flanges and are preferably 10 formed integral with the upper plate 27. One of the arms 21 is disposed between every two of the webs 29 and said webs serve to prevent the flames from being extinguished from all the arms of the burner should wind 15 blow against it. The pipe 24 is connected to a supply pipe 30 in any suitable manner and said supply pipe also opens into a circular distributing pipe 31 located below the partition 5. This distributing pipe has a series of 20 jets 32 one or more of which is located below and within each nipple 6 so as to direct fuel from the pipe 31 into the nipples of the various burners. As indicated at 33 a suitable pressure regulator may be connected to the 25 coil 2 for actuating a valve 34 within pipe 30 to open or close said valve according to the pressure within the coil.

It is thought that the operation of the burner will be fully understood from the 30 foregoing description when read in connection with the drawings. Gas is directed upward into the several nipples 6 and standards 7 by jets 32 and is thus discharged into the compartments 20 in the heads of the 35 burners. These compartments completely surround the cores 9 and the gas is therefore discharged equally into all parts of the caps upon the heads. The air entering the core of each head is discharged radially into the 40 caps so as to commingle with the gas and ignition can therefore occur as the gas mixture escapes through the slits 16. A portion of the air will also escape through the center of the plate 14 so as to further assist in supporting combustion. As the slits open into 45 the space surrounded by the flange 11 of each burner it will be apparent that the flames will be directed outwardly beyond the plate 14 and a substantially circular flame produced. By providing the means described 50 for directing air into the fuel practically complete combustion results. It is of course to be understood that the pilot burner remains lighted under all conditions and by providing 55 the webs 29 and guard plates 25 and 27 there is little danger of the entire flame from said burner being entirely extinguished by a gust of wind.

What is claimed is:

60 1. In a heater the combination with a base and a partition therein having an upstanding nipple opening therethrough, and means for directing fuel into the nipple; of a burner comprising an inclined head for receiving fuel 65 from the nipple, said head having a central

air passage therethrough, and a cap seated within the head having outlet openings in the peripheral portion thereof.

2. In a heater the combination with a base 70 having a partition, there being a nipple upstanding from the partition; of a burner comprising a tubular standard detachably mounted upon the nipple, a head integral with the standard and having a central air passage therethrough, and a flame distributing cap 75 within the head, there being an inclined water channel surrounding the cap and having an outlet.

3. In a heater the combination with a base 80 having a partition, there being a nipple upon the partition, and means for directing fuel into the nipple; of a tubular standard engaging the nipple, an inclined head having a tubular air conducting core centrally disposed therein, said head opening into and inclined 85 in relation to the standard, and an inclined flame distributing cap within the head and surrounding the core, said core opening into and through the cap.

4. A burner comprising an inclined fuel receiving head having an annular supporting shoulder, there being a flange partly surrounding the shoulder and having a cut away portion constituting an outlet, and a cap 90 seated upon the shoulder and having a central portion extending across the end of the head in an inclined plane, said inclined portion being disposed beyond the flange and constituting water shedding means, said cap having fuel outlets surrounding said inclined 95 portion, there being a channel between the cap and flange and below the fuel outlets.

5. A burner comprising an inclined fuel receiving head, and an inclined apertured flame distributing cap partly located within 100 the head, said cap having a central inclined portion disposed beyond or outside of the head and constituting water shedding means, there being an inclined drain channel surrounding the cap and below the apertures 105 and having an outlet, said channel being positioned to receive the shed water.

6. A burner comprising an inclined fuel receiving head having a central air conducting core therethrough, a fuel distributing cap surrounding the core, said core opening into the cap, and a flange surrounding the cap and forming a drain channel between the cap and flange, said flange being cut away to form an outlet for the channel.

7. A burner comprising a fuel conducting standard, a relatively inclined fuel receiving head mounted thereon and communicating therewith, said head having an axially disposed air conducting core, and a cap detachably secured to and surrounding the core, said cap bearing upon the head and having an annular series of outlets, there being a drain channel surrounding the cap.

8. A burner comprising a fuel conducting 130

standard, a fuel receiving head at one end thereof and inclined thereto, said head having an air conducting core therein, and a cap detachably mounted upon the core and within 5 in the head and comprising a plate and an annular apertured flange, said apertures terminating short of the edge of the flange and the said core opening into the cap.

9. A burner comprising an inclined fuel receiving head having an annular supporting shoulder, there being a flange partly surrounding the shoulder and having an outlet therethrough, an apertured cap seated upon 10

the shoulder, said flange and cap forming a channel therebetween and below the apertures in the cap, and a tubular air conducting core extending through the head and opening into the head and through the cap. 15

In testimony that I claim the foregoing as my own, I have hereto affixed my signature 20 in the presence of two witnesses.

ADOLF BELER.
